(57) **CLAIM**

The ornamental design for a cyclometer, as shown and described.

DESCRIPTION

FIG. 1 is a top, front, right side perspective view of a cyclometer showing my new design;
FIG. 2 is a bottom, rear, left side perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.

The broken lines shown in the drawings depict portions of the cyclometer that form no part of the claimed design.
